CLAIM

The ornamental design for a cocktail shaker and chiller apparatus, as shown and described.

DESCRIPTION

FIG. 1 is an exploded perspective view of the cocktail shaker and chiller apparatus in accordance with the principles of the present disclosure illustrating the outer vessel, the container and the cap, and showing our design;

FIG. 2 is an exploded side elevation view of the cocktail shaker and chiller apparatus (the opposite side elevation view being a mirror image thereof);

FIG. 3 is an exploded top plan view of the cocktail shaker and chiller apparatus;

FIG. 4 is an exploded bottom plan view of the cocktail shaker and chiller apparatus;

FIG. 5 is an exploded perspective view of the cocktail shaker and chiller apparatus illustrating the container mounted to the outer vessel;

FIG. 6 is a perspective view of the cocktail shaker and chiller apparatus in the assembled condition illustrating the outer vessel, the container and the cap;

FIG. 7 is a side elevation view of the cocktail shaker and chiller apparatus in the assembled condition (the opposite side, elevation view being a mirror image thereof);

FIG. 8 is a top plan view of the cocktail shaker and chiller apparatus in the assembled condition; and,

FIG. 9 is a bottom plan view of the cocktail shaker and chiller apparatus in the assembled condition.

The broken lines in the drawing views represent unclaimed portions of the cocktail shaker and chiller apparatus which are included for the purpose of illustrating unclaimed environment only, and forms no part of the claimed design.
